(57) **CLAIM**

We claim the ornamental design for a pet carrier, as shown and described.

DESCRIPTION

FIG. 1 is a perspective view of a pet carrier showing our new design.

FIG. 2 is a front elevation view of the pet carrier of FIG. 1.
FIG. 3 is a rear elevation view of the pet carrier of FIG. 1.
FIG. 4 is a left side elevation view of the pet carrier of FIG. 1.

FIG. 5 is a right side elevation view of the pet carrier of FIG. 1.

FIG. 6 is a top plan view of the pet carrier of FIG. 1; and,
FIG. 7 is a bottom plan view of the pet carrier of FIG. 1.
The broken lines in the drawings illustrate portions of the pet carrier that form no part of the claimed design.
